DIFFERENTIAL STAGE LIFT FLOW DEVICE,
VELOCITY CONTROL

Alexander Boynton, San Antonio, Tex.

Application December 8, 1939, Serial No. 308,321

4 Claims. (Cl. 103—232).

My invention relates to flow devices for wells, especially oil wells.

The principal object is to start and flow wells by the expansive force of compressed air or gas at low pressures and low gas-liquid ratios.

Another object is to harness the differential force in combination with the momentum of the flowing liquid to admit lifting energy into the tubing during the prevalence of low differentials and slow velocities of the educed liquid and to cut off the supply of such energy at pre-determined higher differentials and greater velocities of such liquid.

Another object is to provide such a device having an opening through which swabs and other tools will pass.

I accomplish these objects by employing a tubular shell mounted within a nipple forming part of the tubing, the shell having a series of yieldable springs or discs within it adapted to obstruct the flow of liquid through it, a coiled spring being employed to normally urge a plunger controlling the inflow of pressure fluid to its open position by yieldably engaging the shell containing the series of springs or discs upon the plunger; all of which will more clearly appear from the following specification and accompanying drawing, in which—

Fig. 1 is mainly a longitudinal section through the preferred construction.

Fig. 2 is a cross section on the line 2—2, Fig. 1.

Fig. 3 is a cross section on the line 3—3, Fig. 2.

Fig. 4 is a plan view of one of the sheet metal discs cut into yieldable prongs.

Fig. 5 is a cross section on the line 5—5, Fig. 6.

Fig. 6 is a longitudinal section through a modified construction.

Similar reference characters are employed to designate similar parts throughout the several views.

The differential will be understood to be the difference in pressure obtaining in the well within and without the well tubing.

The column of well liquid caused to stand up in the tubing above the depressed liquid level between the tubing and the casing will be referred to as the upstanding column.

Expulsion of liquid from the well will be understood as caused by expansion of pressure fluid admitted into the upstanding column by the flow devices.

The flow devices will be understood as spaced approximately 200 to 300 feet apart in the flow tubing.

The differential force per square inch required

to seat the pressure fluid valves ordinarily will be somewhat greater than the force per square inch exerted by a column of the un-aerated well liquid twice as high as the distance between adjacent devices.

The section 2—2' is identical in the form of the parts where cut with the section 2—2, but is distinguished from the latter section because one of the intersected parts 5 differs somewhat in other places from the part 5 cut by the section 2—2. Likewise, the section 3—3' is identical with the section 3—3, except that the member 11 cut in the latter section differs in other places from the member 1 cut by the section 3—3.

In Fig. 1, illustrating the preferred construction, the tubular shell 1, which may be a steel casting, having the lateral enlargement 1a housing the plunger 3, has threaded engagement with the bushing member 2. By means of the threaded engagement between the actuator base 5 and the actuator clamp sleeve 6, the metallic discs 8 and the metallic rings 9 are firmly secured between the annular shoulders 5d and 6b. Each of the discs 8 is secured between two of the rings 9, the discs and rings being closely received within the sleeve 6.

The discs 8, which may be of thin spring steel plates or may be of fabric interwoven with spring steel wires, are cut as shown at 8b, 8c, and 8d (see Fig. 4), in order to make them yieldable, so that swabs and other tools may be run through the tubing. The cut away portion 8d forms the prongs 8e but, in order to avoid unnecessary dismembering of the discs, the other cuts do not extend to the periphery. In assembling, the discs may be staggered so that the cuts of one disc will be out of registration with the cuts of the others.

Each disc has a central opening, these openings being of graduated diameters forming the oppositely flared opening 8a which allows easy passage for swabs or other tools. When a swab or other tool is run in, the discs flex in the direction of the slightly flared circular surface 5c, and when the tool is withdrawn, the discs flex in the opposite direction of the other flared circular surface 6c. The opening 8a thus becomes expandable to the full size of the opening through the tubing and overcomes the objection to a restricted opening through the tubing. It will be observed that the rounded surfaces 2a, 6d, 5e, and 1f are also adapted to allow free passage of a swab.

The assembly of the members 5 and 6, freely slidable within the shell 1, is normally engaged

resiliently upon the annular shoulder $1e$ by the expansive force of the coiled spring 10 , having slight clearance over the upstanding tubular extension $5a$ of the member 5 and larger clearance outside, the upper end of this spring being engaged under the bushing 2 , while the lower end rests upon the member 6 .

The extension $5a$ is freely slideable within the member 2 , and the depending tubular extension $5a$ is similarly slideable within the member 1 for a distance somewhat greater than the plunger travel necessary to seat the valve $3a$.

The balls 7 are free within peripheral openings in the members 5 and 6 out of which openings they protrude slightly to form rolling guides for these members during their movements within the shell 1 . The members 5 , 6 , 7 , 8 , and 9 will be referred to as the disc assembly.

The plunger 3 , having such as $\frac{1}{4}$ inch clearance within the chamber $1d$, is retained by the bushing 4 , having the intake opening $4a$, over which the plunger acts as a check valve to prevent drainage of well fluid back through the device at conclusion of the flowing operation.

The neck $3b$ of the plunger may engage the member 5 or have slight clearance with it in the idle position of the device, as shown in Fig. 1, but during the flowing operation, the neck $3b$ will constantly engage the member 5 as the disc assembly moves. This assembly will be urged upwardly by the well liquid flowing through it and the plunger will be urged upwardly by the differential force.

In operation, the pressure fluid enters the upstanding column of well liquid in the tubing 16 via the intake opening $4a$, the plunger chamber $1d$, the opening $1c$, the recess $5f$, and the discharge ports $5b$.

The force required to compress the spring 10 far enough to allow the valve $3a$ to engage its seat $1b$ at, for example, 100 pounds differential, is exerted partly by the resistance encountered by fluid in passing through the opening $8a$ and partly by the lifting force of the plunger exerted by the neck $3b$ engaged under the member 5 .

In Fig. 6, illustrating a modified construction, the tubular shell 11 , which may be a steel casting, having the lateral enlargement $11a$, has threaded engagement with the coupling member 12 . The cage 13 is freely slideable within the shell 11 and has its lower unslotted portion $13b$ normally landed resiliently upon the annular shoulder $11b$ of the member 11 by the expansive force of the coiled spring 10 having slight clearance over the upper unslotted portion $13a$ of the member 13 and within the shell 11 and having its ends engaged between the annular shoulder $12a$ of the member 12 and the annular flange $13e$ of the cage 13 . The upper portion $13a$ is slideable within the member 12 for a distance slightly greater than the plunger travel required to engage the valve $3a$ upon its seat $1b$.

The cage 13 has a plurality of longitudinal slots $13c$ forming the posts $13k$ opposite the annular recess $13d$. Within these slots, the pre-formed baffle springs 15 are secured by the snap ring 14 , engaged within an annular recess formed within the annular projection $13f$ of the member 13 , and by the snap ring $14'$, engaged within another annular recess within the other annular projection $13f'$ of the member 13 .

The baffle springs 15 have heads $15a$ somewhat wider than the slots $13c$ which heads prevent the springs from being dislodged from their slots while the snap rings 14 and $14'$ are in place, as

shown. The recesses $13g$ and $13g'$ allow travel room for the spring heads $15a$ when the arched portions of the springs 15 are forced outwardly into the slots $13c$. Thus, provision is made for running swabs or other tools through the tubing. The central opening through the cage 13 may be the same size as the tubing passage, thus enabling swabs or other tools, as large as the tubing will take, to pass through these devices.

When a swab is run through, the baffle springs will slide within their respective slots $13c$ until their lower heads $15a$ land upon the flanged lower end of the member 13 ; whereupon the upper heads $15a$ will rise within the recess $13g$ as the springs straighten in allowing the swab to pass downward. The baffles then resume their normal position as shown in Figs. 5 and 6. When the swab is withdrawn, the upper heads $15a$ will be forced upwardly against the flange $13e$; whereupon the lower heads $15a$ will move downward within the recess $13g'$ as the springs again straighten to allow the swab to pass. The central opening $15b$ (Fig. 5) normally is restricted by the preformed springs 15 , as appears in Fig. 6, but will increase as necessary to allow large volumes of well liquid to pass through in a similar manner to the way it will enlarge to allow for the passage of swabs and other tools.

The operative relation between the plunger and the movable baffle assembly, composed of the members 13 , 14 , $14'$, and 15 , is the same as was explained for the somewhat similar construction in Fig. 1.

In each form of the invention, the yieldable baffle member operates as a power take-off upon the flowing well fluid to assist the plunger valve in closing and to keep it closed during the prevalence of high differentials, at such times as no more pressure fluid is required to maintain the proper rate of well flow. The yieldable baffles also cushion the fall of liquid slugs resulting from the occasional breaking through of pressure fluid; thereby minimizing the harmful effect of slippage tending to open lower valves.

Four forces are involved in the operation of this device. The pressure fluid acting under the plunger 3 and the force of the well liquid exerted upon the yieldable discs 8 in Fig. 1, or against the baffle springs 15 in Fig. 6, are the two valve seating forces. Opposed to these forces are the force of the spring 10 and the pressure exerted by the upstanding column upon the valve $3a$ which are constantly tending to unseat this valve.

The force of the upstanding column and the force of the flowing fluid are variable, while the force of the spring and the force of the pressure fluid are constant at all levels.

It will be observed that the pressure fluid control valve $3a$ is normally open until closed by the combined force of the differential and the force of the fluid flowing through the tubing.

It is apparent that many minor changes can be made in the constructions illustrated and that equivalents can be substituted for parts shown; and I reserve the right to make such changes and substitutions within the scope and purpose of the stated objects and appended claims.

What is claimed is:

1. Well flowing apparatus of the character described comprising a conduit in which a column of liquid may be lifted, a valve body in said conduit having a passageway communicating between the interior and exterior thereof, a valve element movable in said passageway by pressure fluid flowing to the interior of the body, a baffle

assembly within the body having a flow passage therethrough and movable by the varying velocity head of the moving column of liquid within the conduit and body, said assembly engaging the stem of the valve to effect control of the valve movement, said baffle assembly including yieldable inwardly extending members adapted to increase the effective passage through the body as the velocity head within the body increases.

2. A well flowing device comprising a valve body having an axial bore, a baffle assembly having a flow passage therethrough and movable within said bore, said assembly including a plurality of flexible members extending inwardly toward the axis of the bore, a passage in the wall of the body, a valve in said passage having a stem in engagement with said assembly, and means resiliently urging the assembly downwardly to keep the valve open.

3. In a well flowing device of the class described the combination of a valve body having a pas-

sage through the wall thereof, a valve in said passage, a stem on said valve and extending to the interior of the body, a cage movable axially within said body, means resiliently urging said cage into engagement with said stem to hold the valve open, and a plurality of axially flexible discs mounted within said cage to provide a variable passage through the body for the changing velocity head of liquid passing therethrough.

4. In a well flowing device of the class described the combination of, a valve body having an internal enlargement, a cage movable within said enlargement, a plurality of bowed springs movably mounted in the walls of the cage and extending longitudinally thereof to form a restricted passageway of variable cross section, a passage in the wall of the body from the exterior to the interior thereof, a valve in said passage, and a stem on said valve engageable by said cage whereby the flow of fluid through said valve is controlled.
